UNITED STATES PATENT OFFICE.

JOHAN VIKTOR BLOMQUIST, OF STOCKHOLM, SWEDEN.

ROTARY STEAM GENERATOR.

Application filed May 15, 1925, Serial No. 30,549, and in Sweden January 29, 1925.

To avoid the inconveniences inherent in usual steam boilers, steam generators have been constructed for very high pressures comprising rotary tubular elements which rotate at such a great velocity that the water is distributed in an annular layer on the peripheral interior of the tubular elements for the purpose of obtaining a uniform temperature over the whole surface of the tubular elements. To effect this result the velocity of rotation is about 300 revolutions per minute.

It is obvious that a uniform temperature of the whole peripheral surface may also be obtained when the tubular elements rotate with such low velocity that the water does not follow the rotation, the temperature of the peripheral surface becoming however somewhat higher than in the first named case. The increase of temperature thus produced may however, in adopting an appropriate number of revolutions, be kept sufficiently low to prevent impairing the strength of the material.

Similar steam generators rotating with low velocity are already to be found in the patent literature, for instance in the British patent specification No. 1218 of the year 1876. As disclosed by this patent the tubes of the boiler are filled with water up to about half, and the steam is discharged into an elongated receptacle and thence to the points of utilization. At the time said patent was granted, only pressures of a few atmospheres had been utilized, so that the tubes of the boiler could be made with a diameter of sufficiently large size as to be able to use water inlet and steam outlet conduits of sufficiently large diameter, this being the condition necessary for the proper control of the level of the water in the boiler tubes, which control according to the said patent is effected either manually or automatically. The levels of water in the receptacle and in the boiler tubes are thus always at the same height.

The higher the steam pressure the smaller must be the diameter of the boiler tubes (for instance only 12 inches for 100 atmospheres) so as to be capable to resist the stresses to which the material is subjected. For this reason the device according to the cited patent cannot be utilized.

The present invention has for its object to provide apparatus which permits utilizing, even for very high pressures, boiler tubes having a relatively small diameter and rotating

with such low velocity that the water does not rotate with the tubes, and to obtain at the same time a sufficient difference in height of the water for the control of the supply of water.

Two modifications of the invention are diagrammatically illustrated in the accompanying drawings. Fig. 1 shows a vertical section of the one embodiment and Fig. 2 shows a top plan view of the same, parts being broken away. Figs. 3 and 4 show in similar respective views another modification.

Two boiler tubes are shown in the drawing, and the movement of rotation is transmitted from the one to the other by means of toothed wheels 1, which in turn is driven by a motor of any appropriate type, for example, a steam engine.

Referring to Figs. 1 and 2 the feed water is fed through the conduit 2 to the receptacle 3, whence it passes to the boiler tubes 5 of substantially cylindrical shape through straight non-rotatable conduits 4. In a modification, shown in Fig. 3, the one end of the conduits 4 is bent downwardly in the respective boiler tube 5 and terminates near the lower generatrix of the latter and the other end of the conduit extending into the receptacle 3 is also bent downwardly but terminates at a lower level than the end in the boiler tube. In order to obtain the desired siphon effect the conduits 4 must of course be emptied of air before the boiler is started which may be effected by suitable means not shown. The steam is discharged through the non-rotatable conduits 6 which are bent upwards and terminate near the upper generatrix of the boiler tubes 5. The other end of each of the conduits 6 opens into the steam space of the receptacle 3, whence the steam is discharged to the points of utilization after having previously been superheated if desired.

It is obvious that the height of the water level in the boiler tubes depends upon the intensity of the evaporation in the same and also upon the cross sectional area of the steam discharge conduits. The smaller the said area is the larger will be the difference in height between the water levels in the boiler tubes at full and no or feeble evaporation. The water level in the boiler tubes is obviously lowest for the greatest evaporation, because the velocity necessary at the entrance of the steam into the conduits 6 and the resistance of friction in the latter are then

obviously greatest and because the steam will then press the water back through the conduits 4 into the receptacle 3. Thus, by giving the conduits 6 and 4 proper dimensions, the water level in the boiler tubes may be kept within appropriate limits.

To avoid a boiling so as to cause a shortage of water in case the evaporation should become too great, the feeding conduits 4 may be provided with larger conduits 8 surrounding the former and being in communication with the steam space of the receptacle 3 through the conduit 9. The area of the pipes 6 from the cylinders must, of course, be chosen so great, that the water level in the hardest working cylinder, also when great differences of evaporation in the different cylinders take place, cannot sink normally under the upper generatrix of the pipe 8. In case the evaporation in a certain cylinder should be extremely great in comparison with the other cylinders it would be possible that the water level in the hardest working cylinder would sink below the said generatrix. Since thereby a part of the steam is permitted to escape through the opening thus left free of the annular area between the pipes 7 and 8, the resistance to the escape of the steam from the hardest working cylinder is reduced and then an equilibrium between the water levels is obtained, on account of which fact the water level in the hardest working cylinder is prevented from remaining lower than the said upper generatrix.

By this means the outlet area for the steam from the cylinder, in which the water level has sunk below the upper generatrix of the pipe 8, is increased. Since the velocity head and the frictional resistance are decreased in proportion to the increase of the free area of the steam outlet, the water level in the cylinder having the greatest efficiency cannot remain lower than said upper generatrix on account of the total pressures in the cylinders being balanced.

The purpose of the receptacle 3 is to serve as an indicator for reading off the water level in the rotating boiler tubes 5 by means of the gauge glass 7. According to the water level thus read off, the supply of feed water can be regulated in the same manner as in ordinary boilers.

As the water level in the boiler tubes decreases when the evaporation increases the temperature of the peripheral surface will obviously also increase in proportion to the evaporation. In order to obtain approximately the same temperature of the peripheral surface independently of the intensity of the evaporation, the engine 24 which drives the boiler tubes through the intermediary of a pinion 25 in mesh with one of the gear wheels 1 may be adapted to revolve at different speeds in such a manner that the speed is in-

creased according to the increase in evaporation, that is to say according to the decrease of the water level in the boiler tubes.

This may be carried into effect in a known manner by means of a float or the like which opens or closes the steam supply valve for the steam engine 24 driving the boiler tubes 5, whereby the speed of the latter may be respectively increased or decreased. An example of such device is shown in Fig. 1. A 75 housing 14 is in communication with the steam space and water space of the receptacle 3 by means of the pipings 15 and 16 respectively. In the housing depends, on a spring 17, a bell 18 having its lower portion immersed in a mercury trap 19. The remainder of space in the housing and also the pipings 15 and 16 are filled with cold water. Therefore, the water column above the bell always is higher than that underneath the bell and thus tends to press the bell down, but this tendency is counteracted by the spring 17, the force of resiliency of which is obviously altered according to the water level in the receptacle 3. The bell 18 is provided with a 90 rod 20 which is connected to a balanced steam valve 21, through which the steam passes in the direction of the arrows through the piping 26 to the steam engine 24 which drives the boiler tubes 5. When the water level in the receptacle 3 rises, which is the same as an increase in evaporation in the boiler tubes 5, the valve 21 opens wider the higher the water level in the receptacle 3 rises on account of the pressure of the higher water column acting upon the bell 18 from underneath. In consequence steam will pass in proportionally greater degree to the steam engine 24 whereby its speed and thus that of the boiler tubes 5 will be increased. When the water 105 in the receptacle 3 decreases, then also the bell 18 will move downwardly, thus somewhat closing the valve 21, and consequently diminishing the supply of steam to the engine 24 which therefore will operate slower.

It is finally obvious that great axial pressures will be produced which should be absorbed by axial thrust bearings or by a frame provided at the ends of the boiler tubes and kept together by means of stay rods. To 115 avoid such contrivances the conduits 6 and 8 may instead be kept in place by means of a suitable stay including a tension rod 10 secured to one end of said tube, and to brace rods 10' at the other end.

What I claim as my invention, and desire to secure by Letters Patent, is:—

1. A high pressure steam generator comprising in combination, a plurality of substantially cylindrical smooth tubular elements of relatively small diameter, each having a non-rotatable steam outlet at the one end thereof and a non-rotatable water inlet at the other end thereof, means associated with each element to rotate the same, a feed 125

water supply controlling receptacle arranged externally of the tubular elements and partly filled with water, the said water inlet being in communication with the water space of the controlling receptacle, and external means connecting the steam outlet of each element with the upper space of the controlling receptacle.

2. A high pressure steam generator comprising in combination, a plurality of substantially cylindrical smooth tubular elements of relatively small diameter, each having a non-rotatable steam outlet at the one end thereof and a non-rotatable water inlet conduit at the other end thereof, means associated with each element to rotate the same, a feed water supply controlling receptacle arranged externally of the tubular elements and partly filled with water, the said water inlet conduit being in communication with the water space of the controlling receptacle, both ends of said water inlet conduit being bent down and external means connecting the steam outlet of each element with the upper space of the controlling receptacle.

3. A high pressure steam generator comprising in combination, a plurality of substantially cylindrical smooth tubular elements of relatively small diameter, each having a non-rotatable steam outlet at the one end thereof and a non-rotatable water inlet at the other end thereof, means associated with each element to rotate the same, a feed water supply controlling receptacle arranged externally of the tubular elements and partly filled with water, the said water inlet being in communication with the water space of the controlling receptacle and external means connecting the steam outlet of each element with the upper space of the controlling receptacle and a conduit surrounding the water inlet at the one end in communication with the water space of the tubular element and at the other end in communication with the upper space of the controlling receptacle.

4. A high pressure steam generator comprising in combination, a plurality of substantially cylindrical smooth tubular elements of relatively small diameter, each having a non-rotatable steam outlet at the one end thereof and a non-rotatable water inlet at the other end thereof, means associated with each element to rotate the same, a feed

water supply controlling receptacle arranged externally of the tubular elements and partly filled with water, the said water inlet being in communication with the water space of the controlling receptacle, an external conduit connecting the steam outlet of each element with the upper space of the controlling receptacle, a throttle valve means arranged in said conduit, a floating device in the controlling receptacle connected to the throttle valve means and adapted to close the latter when the water level in the receptacle decreases.

5. A high pressure steam generator comprising in combination, a plurality of substantially cylindrical smooth tubular elements of relatively small diameter, each having a non-rotatable steam outlet at the one end thereof and a non-rotatable water inlet at the other end thereof, means associated with each element to rotate the same, a separate means to govern the speed of the rotating means so that its speed may vary indirectly as the height of the water level in the tubes, a feed water supply controlling receptacle arranged externally of the tubular elements and partly filled with water, the said water inlet being in communication with the water space of the controlling receptacle and an external conduit connecting the steam outlet of each element with the upper space of the controlling receptacle.

6. A high pressure steam generator comprising in combination, a plurality of substantially cylindrical smooth tubular elements of relatively small diameter, each having a non-rotatable steam outlet at the one end thereof and a non-rotatable water inlet at the other end thereof, means associated with each element to rotate the same, a feed water supply controlling receptacle arranged externally of the tubular elements and partly filled with water, the said water inlet being in communication with the water space of the controlling receptacle, an external conduit connecting the steam outlet of each element with the upper space of the controlling receptacle and stay devices in the interior of each tubular element interconnecting the steam outlet and the water inlet.

In testimony whereof I have signed my name to this specification.

JOHAN VIKTOR BLOMQUIST.
